LOCK BINDER

Filed Nov. 18, 1931

UNITED STATES PATENT OFFICE

HUGH G. BUCHAN, OF PHILADELPHIA, PENNSYLVANIA

LOCK BINDER

Application filed November 18, 1931. Serial No. 575,722.

This invention relates to a binder lock which is adapted for releasably locking two compression members together, but which is adapted for other uses.

5 It is an object of this invention to provide a locking mechanism upon one of the compression members for engaging suitable impaling or locking posts for holding the sheets therebetween in compressed relation, 10 but which may be readily released by the manual manipulation of levers which are adapted to be given an upward pull and which carry the upper compression member therewith.

15 The invention comprises the novel structure and combination of parts hereinafter described and more particularly pointed out and defined in the appended claims.

In the accompanying drawing which illustrates a preferred form of this invention, and in which similar reference numerals refer to similar features in the different views:

20 Figure 1 is an elevational view of a pair of compression members which are latched together by locking mechanism involving this invention.

25 Figure 2 is a top plan view of the structure shown in Figure 1 and illustrating the casing removed from one of the locking mechanisms.

30 Figure 3 is an enlarged sectional view taken upon the line III—III of Figure 2 illustrating one of the locking mechanisms in section.

35 Figure 4 is a view similar to Figure 3 illustrating the locking mechanism in its unlocked position.

40 In connection with this invention, there has been illustrated a lower clamping head or compression member 1 of a loose leaf binder and an upper clamping head or compression member 2. Posts 3 extend from the lower member 1 to which they are attached and extend through suitable apertures in the upper member 2. These posts 3 also extend through apertures in the bearings 4 which are attached to the upper member 2 as will later more fully appear.

45 50 The members 4 are provided with upwardly

diverging apertures or slots 5 which communicate adjacent their lower ends with the apertures through which the posts pass, and within these slots are positioned suitable rollers 6 which are adapted for frictionally engaging the posts 3 for locking the upper member thereto when the rollers are in the lower portion of the slots. The upper outer portions of the bearings 4 are provided with channel-like recesses 7 in which leaf springs 8 are located for bearing upon the top of the rollers 6 and urging the same downwardly into frictional engagement with the posts 3.

55 The outer ends of the leaf springs 8 are anchored beneath washers 9 positioned in the channel grooves 7 and clamped against the bottom of such grooves by means of rivets 10 which extend through the clamping members 2 and secure the casing 11 which extends over the bearings as shown in the right hand view of Figures 1 and 2.

60 65 70 A bifurcated lever 12 having arms 13 that straddle the bearings 4 is associated with each roller 6 for elevating the same. It will be noted that these levers have upturned handle portions at the ends of the bearings 4 and at the opposite ends thereof are turned upwardly under the rollers 6 and are provided with offset shoulders that are pivotally supported in the notch 14 in the top of the bearings 4 located between the two rollers. The outer ends of the levers 12 normally rest upon the top of the compression member 2 and in elevating the same the fulcrum in the notch 14.

75 80 85 90 95 100 To unlock the binder it is only necessary for the operator to engage the two levers of one bearing between a thumb and finger of one hand draw the same together, while the two levers in connection with the other bearing may be engaged by the thumb and a finger of the second hand in a similar way. While the thumb and finger are drawn together they are also given an upward pull for elevating the upper compression member 2. It will be noted that as these levers are elevated they will engage beneath the ends of the rollers 6 which extend beyond the sides of the bearings 4 and shift the

same upwardly in the diverging slots and out of engagement with the posts 13.

When the upper compression member 2 has been unlocked and is in its elevated position it will be frictionally locked in such position as soon as the operator releases the lever 12. The springs 8 will however yield sufficiently so that the upper compression member 2 may be readily forced downward-
10 ly by merely exerting pressure thereon, and as soon as it is in its lowered and compressed position, the springs 8 will immediately force the rollers 6 into frictional engagement with the posts.

15 From the foregoing it will be apparent that a novel form of locking mechanism has been provided for locking a pair of compression members in adjusted position and in which the locking mechanism can be read-
20 ily released by a force which tends to separate the two clamping members and in which the locking mechanism will yield so that the two members may be forced together without disengaging the frictional elements
25 from the posts. It will hence be appreciated that not only is the structure novel but it also produces a novel operation of the parts.

I am aware that many changes may be
30 made and numerous details of construction may be varied through a wide range without departing from the principles of this invention, and I, therefore, do not purpose limiting the patent granted hereon other-
35 wise than necessitated by the prior art.

I claim as my invention:

1. In a binder, a compression member having a post thereon, a second compression member having an aperture for receiving
40 said post, a bearing attached to said second member and having an aperture for receiving said post and upwardly diverging slots extending from said bearing aperture, friction elements located in said slots, yielding
45 means for urging said friction elements into engagement with said posts, and a pair of bifurcated levers pivoted to said bearings and straddling the same and operable for simultaneously elevating said friction ele-
50 ments.

2. In a binder, a lower clamping member having a post thereon, an upper clamping member having an aperture for receiving said post, a bearing attached to said upper
55 clamping member and having an aperture through which said post passes, said bearing having diverging slots extending from said bearing aperture, rollers mounted in said slots, yielding means acting upon said rollers
60 for urging the same into contact with said post, and levers having parallel arms straddling said bearing beneath said rollers pivoted to said bearing for elevating said rollers, said levers being adapted to be engaged
65 by the thumb and finger of an operator's

hand for unlocking the upper clamping member.

3. In a binder, a clamping head having a post thereon, a second clamping head having an aperture to receive said post, a bearing upon the top of said second clamping member, and having an aperture for receiving said post, said bearing having diverging slots extending from the aperture therein, friction elements located in said slots, yielding means acting on said elements for forcing the same against said posts, said bearing having a fulcrum groove between said friction elements, and a pair of levers, each straddling a portion of said bearing and fulcrumed in said fulcrum groove.

In testimony whereof I have hereunto subscribed my name at Philadelphia, Philadelphia County, Pennsylvania.

HUGH G. BUCHAN.
